UNITED STATES PATENT OFFICE.

WILLIAM MOOR BARRY AND EDMOND HALL BECKER, OF MEXIA, TEXAS.

JACK STAND.

Application filed July 31, 1923. Serial No. 654,871.

To all whom it may concern:

Be it known that WILLIAM MOOR BARRY and EDMOND HALL BECKER, citizens of the United States, residing at Mexia, in the county of Limestone and State of Texas, have invented certain new and useful Improvements in Jack Stands, of which the following is a specification.

This invention relates to improvements in jack stands such as are employed in the operation of re-brassing railway car journal boxes, and the object of the invention is to provide a jack stand embodying means for holding the car wheel upon the rail and thus prevent the wheel being lifted with the journal box when the jack is operated to elevate the said box.

More specifically, it is another object of the invention to provide, in a jack stand of this type, a novel construction of means for engaging the car wheel, which means may be readily applied to the wheel and be securely anchored thereon without the employment of extraneous fastening devices, so that with the expenditure of but little time and labor the device may be securely anchored in place.

Another object of the invention is to so construct the anchoring means for the wheel that the same may be engaged with wheels of various diameters.

In the accompanying drawings:

Figure 1 is a perspective view of the jack stand embodying the invention arranged in position for use, the jack to be employed in connection therewith, being omitted from the figure in order to better illustrate the actual invention;

Figure 2 is a vertical longitudinal sectional view through the base of the jack stand and illustrating in elevation one of the anchoring devices constituting a part thereof;

Figure 3 is a vertical front to rear sectional view through the wheel engaging and anchoring member of the device.

In the drawings, the reference letter W indicates a railway car wheel which is to be held to its position upon the rail R at the time the jack (not shown) is being employed to elevate the journal box indicated by the reference letter J. The device embodying the invention comprises a base which is indicated in general by the reference numeral 1 and which may comprise a flat plate either cast or otherwise formed, the plate being provided upon its upper side with an annular upstanding flange 2 constituting a seat

3 for the base of the lifting jack (not shown) set screws 4 being threaded through opposite sides of the flange 2 and being designed to be tightened to bind the base of the jack and thus secure the jack in position upon the base 1, and retain the same against displacement. At one end the base plate is formed with a longitudinal extension 5 which is designed to extend beneath the rail R at a point likewise beneath the wheel W which is to be held to the rail during the jacking operation. At opposite sides of the extension 5, the base plate 1 is provided with ears or bracket portions 6 which occupy preferably a vertical plane and which extend upwardly beside the outer side of the rail R, when the base is placed in position as illustrated in Figure 1 of the drawings. A short length of chain, indicated by the numeral 7, is permanently connected at one end to the upper end of each of the bracket members 6, and a hook 8 is connected permanently to the other end of the said chain.

The car wheel engaging and anchoring member of the device is indicated in general by the numeral 9 and the said device preferably comprises a frame formed from heavy rod material, the frame including a front bar 10, a rear bar 11 extending parallel thereto, and side members 12 which connect the corresponding ends of the front and rear bars. Substantially at their juncture with the ends of the front cross bar 10, the side members 12 are each provided with downwardly extending bends 13 which are open at their upper sides and in which rest the uppermost links 14 of chains 15 which chains are thus suspended in depending relation from the frame 9, the corresponding hooks 8 upon the chains 7 being interchangeably engageable with the links of the chains 15 so as to connect the anchoring member 9 with the base of the device. In order to prevent twisting of the chains 15, swivels 16 are interposed in the said chains at any suitable point in their length, as, for example, adjacent the uppermost link 14. At this point it will be understood that regardless of the diameter of the wheel W, the chains 15 may be adjustably engaged with the hooks 8 so as to extend substantially taut between the anchoring frame 9 and the base of the device.

The intermediate portions of the side members 12 of the anchoring frame 9 are designed to extend across the tread of the car

wheel W at the upper side of the said wheel, and the rear portions of these side members 12, near where they join the rear cross member 11 of the frame, are bent upwardly and 5 rearwardly and thence downwardly as indicated by the numeral 17 so as to provide hook portions to engage over the flange of the car wheel, it being observed that in the applied position of the anchoring frame, the 10 front cross member 10 extends across the outer side of the said wheel, and the rear cross member 11 of the frame extends across the inner side of the said wheel.

Having assembled the supports with the 15 wheel and rail in the manner above outlined, and with the chains 15 extending downwardly at opposite sides of the journal box J, the ordinary lifting jack is mounted upon the base 1 within the seat 3 and secured in place by the set screws 4, the head of the jack engaging beneath the journal box J. The jack may then be operated so as to elevate the journal box and in this operation the downward pull exerted upon the 20 chains 15 and the anchoring frame 9 will serve to hold the wheel W firmly to the rail R and prevent the wheel being lifted with the journal box. As a consequence, when the journal box has been sufficiently elevated, the brass may be readily removed therefrom and a new brass substituted therefor.

Having thus described the invention, what is claimed as new is:

35 1. A lifting jack stand of the class described comprising a jack supporting base,

having a portion to engage beneath a rail and upstanding ears at opposite sides thereof and adapted to bear against the base of the rail, hooks connected to the said ears, an 40 anchoring frame formed to seat over the upper side of a car wheel, and flexible connecting elements extending from the frame and connected with the said hooks.

2. A lifting jack stand of the class de- 45 scribed comprising a jack supporting base having an upstanding continuous flange providing a seat for the base of a jack, a set screw adjustably threaded through the said flange to engage and anchor the said base of the 50 jack, an anchoring member formed to seat over the upper side of a car wheel, and flexible connecting elements depending from the anchoring member and connected with the base. 55

3. A lifting jack stand of the class de- 60 scribed comprising a supporting base having a reduced extension adapted to fit beneath a rail and provided at opposite sides of said extension with upstanding attach- 65 ing ears, an upstanding seating flange carried by the supporting base in advance of the ears, means carried by the flange for engagement with a jack, an anchoring member adapted to fit over the top of a car wheel, and flexible connecting elements depending from the anchoring member and connected with the ears.

In testimony whereof we affix our signatures.

WILLIAM MOOR BARRY. [L.S.]
EDMOND HALL BECKER. [L.S.]
